UNITED STATES PATENT OFFICE

OSCAR H. GREENE, OF SAN JOSE, CALIFORNIA

POULTRY FEED AND WATER TROUGH

Application filed February 4, 1928. Serial No. 251,859.

This invention relates to a feed or water trough for poultry; my principal objects being to provide a trough of this character so constructed that it may be easily adjusted to meet the requirements of day old chicks or full grown hens, so that the fowls of respective sizes will feed naturally at all times; one which is so arranged that baby chicks cannot fall into the water in the trough and drown, regardless of the position in which the trough may be set; which is so constructed as to prevent the poultry stepping in the trough and scattering the feed without preventing their free and unobstructed feeding; one which is sanitary and vermin proof and easily washed; one of a light, readily portable and compact nature so that it is easily handled and will occupy little space in a pen or brooder house; and one which is equally adaptable for water or for feeds of various kinds.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a perspective view of my improved trough shown in its position for the use of full grown poultry.

Fig. 2 is a fragmentary top plan view of the trough at one end.

Fig. 3 is a cross section of the trough shown as set in position for the use of baby chicks.

Referring now more particularly to the characters of reference on the drawings, the body of the trough is preferably of metal such as galvanized sheet iron and comprises a relatively long side and bottom member 1 of rounded or circular cross section and rigid end walls 2. The sides do not form a full circle but are cut away to form an opening 3 along the full length of the trough, said opening being above the horizontal dia- tral plane of the trough and being of a width

considerably less than the diameter of the trough.

The trough is adjustably supported on a pair of brackets or cradles which comprise horizontal and transversely extending ground engaging members 4 and upstanding spring arms 5 which are curved to conform to the curvature of the sides of the trough and frictionally engage the same on opposite sides.

Extending the full length of the trough on a level with the opening 3, are transversely spaced and closely wound helical tension springs 6 of considerable flexibility. At their ends the springs are adapted to short rod or wire stems 7 which at their outer ends are provided with rigid loops 8. The end members 2 of the trough have transversely spaced vertical slots 9 cut down from the top a certain distance, which slots removably receive the stems 7 therein. The loops 8 are then outwardly of the trough and serve not only as stops to cause the springs to be maintained under a certain tension, but also as finger engaging elements to enable the springs to be readily placed in or removed from position. The slots are so disposed that the springs will be parallel to each other and to the side edges of the trough opening and the spacing between the respective springs and the adjacent side edges of said opening substantially the same.

In operation the trough is adjusted in the brackets so that for full grown hens the opening 3 is horizontally disposed as shown in Fig. 1, while for baby chicks it is set at an angle so that one side edge of the opening is correspondingly lowered to whatever extent is necessary. In the first position the full capacity of the trough is available for feed or water, as is necessary to take care of the relatively great consuming capacity of full grown hens; while in the second position the capacity of the trough is lessened and it cannot possibly hold enough water to drown small chicks even if they could step into the trough. Also as will be evident, one side of the trough is lowered so that the opening from which the chicks take their feed is in a

convenient position for the natural feeding of the small chicks.

The springs form a sort of grating over the opening preventing either small chicks or full grown hens from actually stepping into the trough while not interfering with their free feeding or drinking, since the springs will readily flex or yield laterally whenever they are engaged by the head of the fowl.

10 The springs being readily removable from the trough permit of easy and thorough cleaning of the latter when necessary. The trough may of course be made in different sizes, both as to length and diameter, so as 15 to alter the capacity according to different requirements and size of flocks.

From the foregoing description it will be readily seen that I have produced such a device as substantially fulfills the objects of 20 the invention as set forth herein.

While this specification sets forth in detail the present and preferred construction of the device, still in practice such deviations from such detail may be resorted to as do 25 not form a departure from the spirit of the invention, as defined by the appended claims.

Having thus described my invention what I claim as new and useful and desire to secure by Letters Patent is:

30 1. A poultry feed device comprising a trough member having a longitudinal opening, and a helical tension spring extending lengthwise along the opening from end to end thereof and disposed in transversely 35 spaced and parallel relation to the side edges of the opening.

2. A poultry feed device comprising a trough member having a longitudinal opening, and helical tension springs extending 40 lengthwise of and continuously along the opening and disposed in transversely spaced and parallel relation to each other and to the side edges of the opening, stems attached to the ends of the springs, and enlargements on 45 the outer ends of the stems; the ends of the trough having vertical slots cut down from the top thereof to removably receive the stems therein.

In testimony whereof I affix my signature.

50 OSCAR H. GREENE.
